(57) **CLAIM**

The ornamental design for a filter assembly stand, as shown and described.

DESCRIPTION

FIG. 1 is a first perspective view of a first embodiment of the filter assembly stand of the present invention.

FIG. 2 is a second perspective view of the first embodiment of the filter assembly stand of the present invention.

FIG. 3 is a front view of the first embodiment of the filter assembly stand of the present invention.

FIG. 4 is a rear view of the first embodiment of the filter assembly stand of the present invention.

FIG. 5 is a left-side view of the first embodiment of the filter assembly stand of the present invention.

FIG. 6 is a right-side view of the first embodiment of the filter assembly stand of the present invention.

FIG. 7 is a top view of the first embodiment of the filter assembly stand of the present invention.

FIG. 8 is a bottom view of the first embodiment of the filter assembly stand of the present invention; and,

FIG. 9 is a view of the first embodiment of the filter assembly stand of the present invention illustrating environmental context holding two filter unit assemblies together. The view labels used herein to denote, front, rear, left-side, right-side, top and bottom views are for convenience only and should not be interpreted as limiting her orientation of the bracket.

The broken lines in the Figures are for illustrative purposes only and form no part of the claimed design.
